INFANT'S WALKER

Ralph B. Lay, Columbus, Ind., assignor to Hamilton
Cosco, Inc., Columbus, Ind., a corporation of Indiana

Filed Aug. 29, 1960, Ser. No. 62,042

Term of patent 14 years

(Cl. D14—14)

FIG. 1 is a side elevation of an infant's walker showing my new design;

FIG. 2 is a front elevation thereof; and

FIG. 3 is a perspective view thereof.

The characteristic features of my design for the infant's walker shown reside in the generally A-shaped leg frame and the cantilevered seat supported on said leg frame.

I claim:

The ornamental design for an infant's walker, as shown and described.
